[57] CLAIM

The ornamental design for a commode cleaning device, as shown and described.

DESCRIPTION

FIG. 1 is a front, top and side perspective view of the commode cleaning device embodying the design of the present invention;

FIG. 2 is a front elevational view thereof;

FIG. 3 is a rear elevational view thereof;

FIG. 4 is a side elevational view thereof, the opposite being a mirror image of the side shown in FIG. 4;

FIG. 5 is a top plan view thereof;

FIG. 6 is a bottom plan view thereof; and,

FIG. 7 is a side elevational view thereof, showing a toilet in broken lines for illustrative purposes only and forming no part of the claimed design.
